(57) **CLAIM**

The ornamental design for a lawn mower with charging device, as shown and described.

DESCRIPTION

FIG. 1 is a front perspective view of a lawn mower with charging device, showing our new design; FIG. 2 is a rear perspective view thereof; FIG. 3 is a front view thereof; FIG. 4 is a rear view thereof; FIG. 5 is a left side view thereof; FIG. 6 is a right side view thereof; FIG. 7 is a top view thereof; FIG. 8 is a bottom view thereof; and, FIG. 9 is an enlarged view of the area labeled 9 in FIG. 1. The broken lines in the drawings illustrate the portions of the lawn mower with charging device, which form no part of the claimed design.

1 Claim, 9 Drawing Sheets
